UNITED STATES PATENT OFFICE.

JUAN DIEGUEZ Y LOPEZ AND FRANCISCO ALCAÑIZ Y BASCOMPTE, OF HABANA, CUBA.

LIP-GUARD.

1,344,179.

Specification of Letters Patent. Patented June 22, 1920.

Application filed April 13, 1920. Serial No. 373,547.

To all whom it may concern:

Be it known that we, JUAN DIEGUEZ Y LOPEZ and FRANCISCO ALCAÑIZ Y BASCOMPTE, respectively citizens of the Republic of 5 Cuba, and residents of Habana, Cuba, have invented certain new and useful Improvements in Lip-Guards, of which the following is a specification.

This invention relates to lip guards; and 10 its object is to provide an extremely simple and inexpensive device which may be readily attached to an ordinary glass, cup or other drinking vessel in such a way as to effectively prevent contact of the lips with 15 the edge of the glass, and which may be detached therefrom with equal facility and, if desired, put aside by its owner for subsequent re-use.

The invention also resides in the provision 20 of a device of the character above indicated, which is so constructed as to give notice to the original purchaser in case of its having been previously used.

Other and further objects and advantages 25 will be set forth and become apparent in the course of the following description; but it is to be understood that the invention is not limited to the precise structural details of the embodiment described, but is susceptible 30 of modification and changes within its scope as hereinafter claimed. Parts and features of the invention may be also utilized without others, and in other and different environments.

35 In the accompanying drawing:

Figure 1 is a perspective view, showing the invention in use;

Fig. 2 is a rear elevation of the invention; and

40 Fig. 3 is a vertical section on line 3—3, Fig. 2.

The invention, as represented in the drawing, takes the form of a clip or guard, constructed from a single strip or blank of suitable sheet material, metallic or non-metallic, but preferably resilient, and which is folded upon itself to provide outer and inner wings or members 1 and 2 and a connecting portion or bend 3. The latter portion 45 is disposed at the tops of the wings, as shown, so that the device as a whole may be regarded as having an inverted U shape in vertical section; and the said wings or members, as well as the part 3, are curved 50 transversely so as to fit conformably against the outer and inner surfaces of the wall of

the glass 4 when the guard is in place. Both wings have their lower portions somewhat pointed, and the extremity of one of them, in this instance the inner wing or member 60 2, is slightly out-turned, as indicated at 5, thus providing a shoulder or projection which facilitates the removal of the device from the glass. The wings converge slightly toward each other, so as to grip the wall 65 of the glass more tightly, and in the construction illustrated are shown as having their lower portions arranged in the manner just explained; but it is to be understood that the converging portions may be 70 located elsewhere than at the lower or free ends of the wings and that the latter may even be made to diverge at their free ends.

In order that the purchaser of the device may assure himself that it has never 75 before been used, means are provided whereby any previous use will be visibly indicated. Such means may be of two types, either or both of which may be adopted, one of the means in question being governed 80 by the attachment of the device to the drinking glass, and the other one by the chemical action upon it of the water or other liquid with which the glass is filled. The first-mentioned means comprises a seal 6 of 85 some easily frangible or rupturable material such as wax, paper, etc., which is located in and bridges the space between the free ends of the wings so as to be broken by contact with the edge of the glass when the device 90 is forced thereover. The other protective means consists of a small wafer or the like which is indicated at 7 and is applied to the outer face of the inner wing 2, this wafer being saturated with some harmless chemical 95 solution which, upon coming into contact with the liquid in the glass, will cause it to change its color, or will give some other equivalent indication of previous use.

As an example of the color changing 100 chemical solution just referred to, the following may be mentioned: Any harmless vegetable tincture or extract with which the wafer is saturated, and then covered by a coat of pulverized sugar, which sugar is dissolved by the liquid and consequently exposes the colored wafer.

We claim as our invention:

1. A lip guard for drinking vessels, comprising spaced inner and outer members 110 adapted to straddle the edge of the vessel, and a frangible seal bridging the space be-

tween said members and adapted to be broken by contact with said edge when the guard is fitted thereover.

5 2. A lip guard for drinking vessels, adapted to be supported upon the edge of the vessel and provided with a wafer treated with a chemical solution which, upon contact with the contents of the vessel, will cause the wafer to change color.

10 3. A lip guard for drinking vessels, comprising connected outer and inner members adapted to straddle the edge of the vessel from opposite sides, the inner member being provided with a wafer treated with a chemical solution which, upon contact with the contents of the vessel, will cause the wafer to change color.

15 4. A lip guard for drinking vessels, adapted to be supported upon the edge of the vessel and provided with a pair of protec-

tive devices for giving notice of any previous use of the guard, one of such devices being governed by contact with the edge of the vessel when the guard is being fitted thereupon, and the other device being governed by contact of the liquid contents of the vessel therewith. 25

5. A lip guard for drinking vessels, comprising spaced inner and outer members adapted to straddle the edge of the vessel 30 from opposite sides, and a frangible seal bridging the space between said members and adapted to be broken by contact with said edge when the guard is fitted thereover, the inner member being provided with a wafer treated with a chemical solution which, upon contact with the contents of the vessel, will cause the wafer to change color. 35

JUAN DIEGUEZ y LOPEZ.
FRANCISCO ALCAÑIZ y BASCOMPTE.
